(57) **CLAIM**

I claim the ornamental design for a pet chew, as shown and described.

DESCRIPTION

FIG. 1 is a perspective elevational view of a pet chew showing my new design;

FIG. 2 is a top plan view thereof; the bottom plan view being a mirror image thereof;

FIG. 3 is a left side plan view thereof; the right side plan view being a mirror image thereof; and,

FIG. 4 is a rear plan view thereof; the front plan view being a mirror image thereof.
